UNITED STATES PATENT OFFICE.

WALRAM S. BROWNE, OF BROOKLYN, NEW YORK.

ELECTRICALLY-ACTUATED SWITCH MECHANISM.

SPECIFICATION forming part of Letters Patent No. 586,702, dated July 20, 1897.

Application filed November 25, 1896. Serial No. 613,432. (No model.)

To all whom it may concern:

Be it known that I, WALRAM S. BROWNE, of Brooklyn, in the county of Kings and State of New York, have invented a new and Improved Electrically-Actuated Switch Mechanism, of which the following is a full, clear, and exact description.

My invention relates to an improvement in the mechanism for controlling electrically-actuated switches shown and described in my United States Patent No. 570,373, dated October 27, 1896, which consists, essentially, of certain mechanism by which the switch if thrown to the branch line is left in that position, should a car designed for that line be the next one along.

In my patent above mentioned the switch was in all cases first thrown to the main line and then thrown to the branch line. This made a double movement of the switch in many cases. My present device makes only a single movement whichever way the car is bound.

Reference is to be had to the accompanying drawings, forming a part of this specification, in which similar characters of reference indicate corresponding parts in all the views.

Figure 1 is a cross-section of the controlling device and the magnets for operating the switch. Fig. 2 is a perspective view showing the controlling mechanism for three different switches. Fig. 3 is a horizontal section through the controlling mechanism, and Fig. 4 is a plan view of a track and switch.

The electrical magnets shown in Fig. 1 consists of two solenoids C³ and F³ of unequal power. The solenoid F³, connected to the mechanism so as to throw the switch for the branch line, is the stronger of the two. In Fig. 1 the proportions of the magnets and the track are very much exaggerated in order to show the magnets of a convenient size. The controlling mechanism for operating these magnets consists of a body formed to two insulating-plates A and A', joined in an L shape. The larger one of these, A, is fixed in a vertical plane. To the outer end of the other plate, A', is attached a metal bar B, which at its lower edge is shaped so as to form a portion of the track upon which the trolley runs—that is, its lower edge is made of about the shape and size of the trolley-wire. At

each end the lower edge of this bar is recessed and a hole made through the bar, the recess and the hole being of such a size as to snugly receive the trolley-wire. In fastening the trolley-wire thereto the end of the wire is passed through the hole and then bent over, as shown at e. This makes a quick and sure means of fastening the trolley-wire to the bar. When the trolley-wire is thus fixed to the bar, the lower surfaces of the wire and the bar form a smooth continuous surface of uniform size. The inner surface of the bar B has a recess formed thereon, extending on each side of the center. This recess contains a plate C, which is insulated from the bar B by a layer D of insulating material. The plate C extends as far down as the bar B, and throughout its length forms a portion of the surface upon which the trolley-wheel L will run. When the trolley-wire L is passing over this portion of the bar, it will act as a bridge or connection between the bar B and the plate C.

The plate C is connected to the pin C', which in its turn is connected to a wire C², leading to a solenoid C³. A contact-bar F is pivoted in the vertical member A and projects from the side thereof and is held outward by a flat spring F'. The pivot f forms a connection to which is attached the wire F², leading to the solenoid F³. The vertical position of the contact-bar F will depend upon the switch being operated and will be placed at different elevations for different switches upon the same line.

The head O of the trolley-pole K has a bar P attached thereto and electrically connected with the trolley-wheel. This bar has side projections p placed at such a height as to engage the contact-bar F of those switches which should be thrown by the car carrying the trolley-pole K. The head O will ordinarily have but one of these projections, and all the switches which are to be thrown by this particular car will have their contact-bars placed at such a height relative to the trolley-wire that the projection p will engage them. Switches which are not to be thrown by this car will have their contact-bars arranged at different elevations and will consequently not be affected by the passage of the car. The contact-bars F are so placed relative to the

plate C that they make contact with the projection p before the trolley-wheel L bridges the insulation between the bar B and the plate C. In consequence, if the switch is thrown to the main line the projection p will engage the bar F and conduct sufficient current through the solenoid F³ to throw the switch to the branch line, but the current passes through the plate C to the solenoid C³ and acts to throw the switch to the main line. As the branch-line solenoid is the stronger of the two, the switch will remain thrown for the branch line even when the current passes through the other solenoid. The contact-bar F also maintains contact with the projection p until the contact between the trolley-wheel and the plate D is broken, thus preventing the possibility of the switch being thrown back to the main line. Cars intended for the main line only will not need any projection p for engagement with the contact-bars F, as the trolley-wheel itself will bridge the insulation between the plate C and the bar B and throw the switch for the main line. In Fig. 2 I have shown one trolley-pole of this character and another with the block P and the projections p . It will thus be seen that there can be but one motion of the switch at any time. This simplifies the operation of the device and renders it more certain than the device shown in my previous patent.

In Fig. 4, S represents the rails of what I have referred to herein as the "main line," and S' the rails of the branch line. The joint or switch which is thrown by the magnets is represented by R.

Having thus described my invention, I claim as new and desire to secure by Letters Patent—

40 1. In an automatic switch for electric railways, the combination of an electrically-operated switch-moving mechanism, with a current-switch consisting of a short section of the trolley-wire, which is split vertically into two parts which are insulated from each other, one of said parts being connected with the trolley-wire circuit and the other with the circuit operating the switch-moving mechanism, and adapted to be connected by the passage 45 of the trolley, to supply the current for throwing the switch, substantially as shown and described.

50 2. In an automatic switch for electric railways, the combination of an electrically-operated switch-moving mechanism, comprising two electromagnets of different strength, the weaker being connected to throw the switch for the main line and the stronger to throw the switch for the branch line, with a contact-piece adapted to be engaged by the rolling surface of the trolley-wheel and connected to the weaker or main-line magnet, and a contact-piece extending each side of the first-named contact-piece and connected to the stronger or branch-line magnet, and adapted to be engaged by a special contact-piece projecting from the sides of the trolleys of cars

bound over the branch line, substantially as shown and described.

3. In an automatic switch for electric railways, the combination of an electrically-operated switch-moving mechanism comprising two electromagnets of different strength, the weaker being connected to throw the switch for the main line and the stronger to throw the switch for the branch line, with a contact-piece adapted to be engaged by the rolling surface of the trolley-wheel and connected to the weaker or main-line magnet, and a contact-piece extending each side of the first-named contact-piece and connected to the stronger or branch-line magnet, and adapted to be engaged by a special contact-piece projecting from the sides of the trolleys of cars bound over the branch line, said branch-line contact-pieces upon the trolley and wire occupying different relative positions for different branches, substantially as shown and described.

4. In an automatic switch for electric railways, the combination of electrically-operated switch-moving mechanism, two electromagnets of different strength, the weaker being connected to throw the switch for the main line and the stronger for the branch line, with mechanism operated by the current-collector of all cars, to pass a current through the main-line magnet, and a special contact mechanism upon branch-line cars, adapted to pass a current through the branch-line magnet coincidently with that through the main-line magnet and for a short time before and after the same, substantially as shown and described.

5. An electric-circuit maker for operating a switch, consisting of a bar shaped on its lower edge to correspond to the trolley-wire section, means for attaching the trolley-wire thereto, a longitudinal recess in one side of said bar extending to and including the central line of the bottom edge, and a plate therein but insulated therefrom and adapted to be connected by the trolley-wheel, substantially as shown and described.

6. An electric-circuit maker for operating a switch, consisting of a bar shaped on its lower edge to correspond to the trolley-wire section, a recess in the bottom edge at each end, holes through the bar, connecting with the inner ends of these recesses, a longitudinal recess in one side of said bar, extending to and including the central line of the bottom edge, and a plate therein but insulated therefrom and adapted to be connected by the trolley-wheel, substantially as shown and described.

7. An electric-switch-controlling mechanism, comprising two plates forming an L-shaped insulating-body, a metal bar longitudinally recessed near the middle of its length, a metal plate in said recess and insulated from the first metal plate, the lower edges of said plates being adapted to form a portion of the trolley-track, the longer plate being con-

nected to the trolley-wire and the short plate to the mechanism for throwing the switch to the main line, a contact-bar pivoted in the lower or side member of the insulating-body and adapted to be engaged by side projections on the trolley-head, said contact-bar being located at variable heights in different switches, and connections from the contact-bars to the mechanism for controlling the branch-line switch, said mechanism being

stronger than that for opening the main line, and the connection thereto being made before the connection with the contact-plate for the main line and continuing until the main-line connection is broken, substantially as shown 15 and described.
